UNITED STATES PATENT OFFICE.

GEORGE W. RICH, OF CHICAGO, ILLINOIS, ASSIGNOR TO CHARLES J. BRUSCHKE AND SOPHIE RICKE, OF SAME PLACE.

DESIGN FOR FURNITURE SEAT AND BACK.

SPECIFICATION forming part of Design No. 12,049, dated November 30, 1880.

Application filed July 1, 1880. Term of patent 7 years.

To all whom it may concern:

Be it known that I, GEORGE W. RICH, of Chicago, in the county of Cook and State of Illinois, have invented and produced a new and original Design for Furniture, of which the following is a specification, reference being had to the accompanying drawing, in which is shown a chair-back, in front elevation, embodying my design.

A is a large horseshoe, formed from wood, and having projecting toe and heel calks *a b*, and carved to represent the nail-grooves *c* and the heads of the nails or the nail-holes *d*. The toe and heel calks may be carved with ornamental lines, leaves, or flowers, and the body of the shoe is carved with scrolls, leaves, or flowers *e*. The center of the wooden horseshoe is filled up with upholstering, *B*, plain,

tufted, or piped, as taste may dictate. The wooden horseshoe *A* is supported within and surrounded by an ornamental frame, *C*, which is of carved wood, or may be partly or wholly covered with upholstering.

The design is shown as embodied in the back of a chair, but it is also applicable to single or double back sofas, and to the seats of chairs and sofas, and the tops of foot-stools.

I claim—

The design for furniture seats and backs, consisting of the ornamental horseshoe *A*, the upholstered center *B*, and the surrounding ornamental frame *C*, substantially as described.

GEO. W. RICH.
